UNITED STATES PATENT OFFICE.

BURHANS VAN STEENBERGH, OF GOSHEN, NEW YORK.

APPARATUS FOR MANUFACTURING CARBURETED HYDROGEN GAS.

1,144,800.

Specification of Letters Patent. Patented June 29, 1915.

Application filed July 2, 1914. Serial No. 848,600.

To all whom it may concern:

Be it known that I, BURHANS VAN STEENBERGH, a citizen of the United States, residing at Goshen, in the county of Orange and State of New York, have invented certain new and useful Improvements in Apparatus for Manufacturing Carbureted Hydrogen Gas, of which the following is a specification.

This invention relates to apparatus for manufacturing carbureted hydrogen gas, the construction and advantages of which will be hereinafter set forth.

The matter constituting my invention herein will be defined in the claims.

I will now describe the details of construction of my improved apparatus by reference to the accompanying drawings, in which—

Figure 1 represents a vertical sectional elevation of the generator, comprising the decomposing and fixing chambers and electric heaters. Fig. 2 represents a horizontal sectional view, taken on the line 2—2 of Fig. 1. Fig. 3 represents a perspective view of one of the units or sections of the generator, a portion of said section being broken away to more clearly illustrate the construction. Fig. 4 represents a diagrammatic view, illustrating the manner in which the electric heaters are connected up. Fig. 5 represents, on enlarged scale, a transverse section of an electric heater, such as shown in Fig. 1. Fig. 6 represents, on enlarged scale, a sectional view of an electric heater of modified construction.

The present invention has for its main object the production of an electrically heated generator in which gas may be continuously generated, electric heating units being employed to maintain continuously the exact degree of heat which will best effect the various chemical changes, such as decomposition of steam at the appropriate temperature, the decomposition of hydrocarbon oil into its constituent illuminating gases and vapors, and the recombination of certain gases, without loss of illuminants, or waste of carbon or heat units, so that gas of uniform candle power, and of substantially uniform volume will be continuously generated and delivered for immediate and continuous use for power in a gas engine, or for other purposes, or for storage in a holder for subsequent distribution.

A further object of the invention is to

provide a generator composed of a series of units, each complete in itself, any one of which units may readily be changed, repaired or renewed, in case its operative elements should break down or the unit become defective for any reason, whereby the apparatus may be quickly restored to effective operative condition.

Another object of the invention is to provide means whereby the deposition or partial deposition of carbon, by destructive decomposition of hydrocarbon oil upon the heating surface will be prevented, thereby maintaining the illuminating quality of the gas constant, as the same is produced, and effecting great economy in the operation of the apparatus.

The generator is preferably composed of a plurality of superposed units, each unit carrying one or more electrical heaters and one or more tiles or intercepting members adapted to present a very extended heating surface and cause the superheated steam and the vapors of the hydrocarbon oil to thoroughly commingle and be decomposed to produce a fixed illuminating gas.

Referring now particularly to the drawings, 1 denotes the base of the generator, 2 the top or cover, made of iron or of plate iron with a fire clay lining, between which is located a series of unit sections, alike in form and construction. The base 1 is composed of a pan-like member, having a plate iron shell 3, a lining of asbestos 4, and an interior facing or lining 5 of fire-brick. A pipe 6 opens into this bottom section and through said pipe is introduced a supply of steam and oil. The steam will, preferably, be superheated and be thus used for injecting and atomizing a sufficient proportion of comparatively heavy hydrocarbon oil, commonly called gas oil, to supply the desired quantity of carbon to combine with the oxygen of the steam to form, during decomposition at the required temperature, carbon monoxide and set the hydrogen free. The steam may also be commingled with the requisite proportion of oil vapor and the mixture pre-heated or superheated in a suitable chamber and then supplied in a regulated stream through pipe 6 to the base of the generator. Pipe 6 is provided with a controlling valve α for this purpose; and any suitable automatic regulating device may be used for introducing a continuous stream at a uniform

pressure of steam and oil vapor into the base, or decomposing chamber of the generator.

Each unit section comprises a ring-shaped member 7, made of plate iron and having an inwardly-projecting flange 8, said flange forming the support for the asbestos insulating lining 9 and the fire-brick lining 10, the outer edge of which terminates in substantial alinement with the inner edge of the inwardly-projecting flange 8, thereby forming an annular chamber or recess. One or more tubes 11 (two being shown in the present instance) pass through the walls of the section and are clamped tightly in place by nuts 12, which bear against the washers 13, provided with concave faces adapted to fit the curvature of the shell or ring 7. The unit sections may be rectangular or of other desired shape in cross section.

Mounted in each tube is an electric heater, which may be constructed in the following manner:—Finely-ground silica and finely-ground carbonate of lime are mixed with sodium silicate diluted with water and the pasty mass thus formed is wiped about or molded around a relatively thin cardboard cylinder or tube 14, and then allowed to harden. The outer coating is designated by 15. Mounted within the central portion of the tubular member thus formed is a mass of granular carbon 16, and carbon electrodes 16^a and 16^b are forced into the ends of the cardboard cylinder and tend to compress the particles of granular carbon to a greater or less extent and to thus establish a connection from end to end of the tube between the outer electrodes 16^a and 16^b. The electric heater thus produced is placed within the iron or other tube 11, and the outer coating, formed as above described, serves to insulate the heater from the iron tube and thus prevents short-circuiting. To further insulate the heating member from the tube, suitable dielectric rings or washers 15^a are employed, being preferably located adjacent to the ends of the tube.

The cardboard will, when the current is passed through the heater, be burned away, becoming carbonized and forming in effect a part of the electric conductor.

Owing to the presence of the granulated carbon extending longitudinally through the center of the heaters, and any desired number through the heating unit, the heat will be localized more or less in the plane of each unit section, across and through which the commingled steam and oil vapor must pass on their way to the upper portion of the generator.

In each unit section, or within the walls of the generator, adjacent to the heater tubes 11 are located a plurality of firebrick tiles or bars 17 which may be arranged as

shown in Fig. 1, or in other desired manner. These bars become heated by heat radiated from the electric heaters to approximately the same degree as the tubes 11, and aid by their extended heated surfaces in splitting up hydrocarbon oil or vapor into gases of high illuminating quality, or fixed hydrocarbon gases.

Another form of electric heater, consisting of a hollow tube 15^b, Fig. 6, five inches, more or less, in diameter, made of fire-clay and burned or baked at a temperature of about 3,000 degrees F., the thickness of the tube to be not less than one inch, and the hollow filled with granular carbon, and having carbon electrodes forced into the ends may be used instead of the tubes 11—15—16 above described. The electrodes will compress the particles of carbon to a greater or less extent and thus establish a connection from end to end of the tube.

The body of granular carbon compressed between the ends of the electrodes 16^a and 16^b forms a resistance, by means of which a succession of small or short electric arcs are produced, thus converting the electric energy into heat, thereby heating the tube at that part filled with the granular carbon from the inside to the surface. The heat is localized within the fire-brick walls of the generator or unit sections due to the much greater resistance offered by the granular carbon than that which is offered by the carbon electrodes, and such localized heat is imparted to adjacent tiles 17 and intervening space, so as to produce substantially uniformly heated surfaces and zones. The commingled steam and oil vapor will pass uniformly around, and in contact with, such heated surfaces in their flow up through the decomposing chamber of the generator and will be decomposed to produce carbon monoxide and hydrogen and a percentage of light carbureted hydrogen or marsh gas, which will be carbureted and enriched with illuminants in the upper part of the generator.

Each unit section will be provided with a plurality of lugs or ears 19 which register with similar lugs or ears formed upon the adjacent section or sections in order that the parts may be readily bolted together. Each section will likewise be provided with outwardly-projecting lugs 20 to which hooks and chains, cables or the like may be attached when it becomes necessary to elevate one of the sections with the view of withdrawing the section below and replacing it by a new section.

In assembling the sections they will be so placed that the heaters and tiles of one section will bear at right angles, or substantially so, in relation to the respective heaters and tiles above and below. There is thus produced in the chamber of the generator

numerous tortuous passages through which the gases must pass from the lower to the upper portion of the generator to the outlet pipe 21, located in the upper section, or, if preferred, in the cap or cover, as shown.

Any desired number of tile or fire-clay bars 17 may be arranged in checker-brick form between the electric heaters 14-16 to provide the desired extent of heating surface and to insure that all the steam and oil vapor are brought into contact with numerous heated surfaces for effecting thorough and complete splitting of the oil into constituent gases, or decomposition and recombination of the elements.

The heaters of the alternate sections are connected to bus-bars 22, 23 and 24, 25, respectively, which bars are connected in circuit with a source of energy 26, and a switch 27 controls the circuits.

It will be readily appreciated that an automatic device, such as a thermostat 28, may be located within the retort or the outlet thereof to control the temperature by cutting out or cutting in the circuit according to the variations in the temperature. Thus, the temperature may be kept within fixed limits and practically uniform, and so long as the proper quantity of oil vapor and superheated steam are supplied, the process will be a continuous one.

Above the middle height from the base of the generator—about two-thirds of the height—I provide in the wall of one of the unit sections, two or more oil supply pipes 30, each having a valve *c* and a spray or atomizing nozzle *d* through which a suitable hydro-carbon is supplied for carbureting the gases generated in the lower part of the generator, or for supplying oil to be split into illuminating gases at the appropriate temperature.

A transformer 29 is also, preferably connected with each set or pair of tubular heaters in a unit section for controlling the electromotive forces, and consequently the temperature in each set of heaters. The heat in the different zones of the generator will be regulated and controlled to the exact degree required for either splitting up the oil into its constituent gases of high illuminating power, or producing decomposition of the steam and oil when a large volume of gas is desired.

The iron tubes 11, extending through the generator, will be covered with a fire proof paste or wash 18, preferably composed of lime and magnesium moistened with a very dilute solution of sodium silicate for preventing the deposition of carbon on the iron. This coating also prevents iron, when heated to incandescence, from spoiling the illuminating quality of the gas by causing deposition of carbon; it also aids by catalytic action in splitting up the oil into gases of high

illuminating quality. The fire-clay heater-tube, shown in Fig. 6, may also be coated with this protecting paste, 18.

In case it is desired to generate only high candle power illuminating gas, and not decompose steam, then all the electric heaters will be heated to a constantly maintained temperature of about 800° F. to 850° F. or at that degree which experience shows to be best for heating the steam so that it will exert its catalytic action in aiding to split the petroleum vapors into the largest possible percentage of high illuminant gases of the ethylene and ethene series. The surfaces of the electric heater, composed of coatings of metallic oxids, such as oxid of calcium and oxid of magnesium mixed with dilute silicate of sodium, will be maintained at the best temperature for exerting the desired catalytic action to produce the largest possible percentage of high illuminants from the hydrocarbon oil used. The hydrocarbon oil or vapor injected by jets of steam through pipes 6 and 30 will be split or resolved into gases, such as ethylene-C₂H₄; acetylene C₂H₂; and methane-CH₄.

The heat will never be carried so high as to cause destructive decomposition of the oil vapors and a resulting deposit of part of the carbon in the form of lamp-black or hard carbon or decomposition of steam. Gasification of the hydrocarbon, however, will be complete so that there will be little or no subsequent condensable matter in the gas after passing from the generator. This is practically, a continuous process for generating illuminating gas of uniform quality or candle-power and without waste of hydrocarbons.

The paraffin hydrocarbons, in by far the larger part of the various samples of American and Russian petroleum constitute the principal, and sometimes almost the entire, substance, liquid and solid, of these oils and waxes. The gaseous paraffins in their illuminating quality are far inferior to the gaseous hydrocarbons of the olefin series. By aid of properly regulated heat with auxiliary help of catalytics, such as steam and any one or several of the oxides of calcium, barium, strontium or magnesium in a heated state, these paraffins in heated vapors may be split chemically so as to produce large percentages of permanent gases of the olefin series and of the acetylene series, both of which are far more powerful as illuminants than are the paraffin gases.

In the usual method of converting petroleum or its distillates into permanent gases for illuminating purposes there is more or less separation of solid carbon from the heated petroleum vapor with a correspondingly large production of paraffin gas of low illuminating quality. The deteriorating and wasteful production of this low

grade of gas I avoid by my above described process of making gas.

The electrodes and resistance material being inclosed in the tubes, the heat is more evenly distributed, so that there is no liability to burn, or destructively decompose the oil and form lamp-black or hard carbon, as would occur if the oil was supplied in direct contact with refractory resistance material, through which an electric current was passed.

The exterior coating of oxids of calcium, magnesium, etc., on the heating tubes, acting as a catalytic agent is also an important feature of my invention, for causing the oil to be split into high illuminants of the olefin series, and preventing the deposit of lamp-black or hard carbon.

The process herein described is made the subject of my co-pending application, Serial Number 625467.

In conducting the process of making illuminating gas in this apparatus, the operation is substantially as follows: By supplying or conducting the electric current to the heating tubes in the lowermost three or four of the unit sections—about two-thirds of the height from the bottom—in a properly regulated voltage and amperage, the heating tubes, particularly the portions containing the granulated carbon within the interior fire-brick lining, will be heated to a temperature ranging between 1600° F. and 2000° F., and preferably between 1600° F. and 1800° F. At the same time the electric current is conducted to the heating tubes of the two uppermost unit sections having a voltage and amperage adapted to heat the granular carbon to a temperature ranging between 700° F. and 900° F., so as to heat the tubes and the adjacent fire-clay tiles to about 800° F. or 850° F. Having suitably heated the lower and upper portions or compartments of the generator to the respective temperatures above stated, a supply of superheated steam and pre-heated oil vapor, suitably mingled, is admitted through pipe 6 into the base of the generator. Here decomposition is effected by passage of the steam and oil vapor in contact with the heated surfaces at about 1800° F., causing decomposition of the steam by the oxygen thereof combining with carbon in the oil and setting the hydrogen of the steam free; also partially setting free the hydrogen of the hydro-carbon, but preferably producing a percentage of light carbureted hydrogen or marsh gas (CH_4). This marsh gas or methane will be retained in the gas at about a white heat, ranging between 1500° F. to 1600° F., and will pass on with the hydrogen and the carbon mon-oxid resulting from the decomposition of the steam. These highly heated gases pass upward above the decomposing zone and

into the upper or carbureting zone of the generator, comprising two or more of the unit sections at the top of the generator. As soon as the gases above described are generated, a supply of a suitable hydro-carbon oil is injected through the pipes 30 and discharged therefrom in an atomized condition centrally into the heated gasifying space of the generator. The resulting hydro-carbon vapors will be immediately combined with and carried up by the hydrogen and carbon monoxid into contact with the properly heated surfaces of the electric heating tubes and tiling in the two or more upper unit sections of the generator where a uniform heat is maintained of about 800° F., sufficient to produce complete gasification of all of the hydro-carbon introduced through pipes 30. The gasification here will be so complete and uniform that no carbon will be deposited and no volatile or unfixed vapor will be passed off. The completed fixed illuminating gas will be passed off from the outlet pipe 21 to the usual washer or any suitable cleaning apparatus which may be required. In continuing this process, the high heat of the lower zone or compartment of the generator is constantly maintained, resulting in the complete decomposition of the steam and carbon without deposit of black or hard carbon on the heating tubes or fire-clay tiling. There will be no ash deposited. The upper zone of the generator, called the carbureting compartment, will also be heated to a constantly maintained temperature of about 800° F., so that the hydrocarbon admitted for carbureting the poorer gases will be resolved into its constituent gases, such as ethylene (C_2H_4), and acetylene (C_2H_2), and a percentage of methane (CH_4). The heat will never be carried so high as to cause destructive decomposition of the oil vapors and a resulting deposit of part of the carbon in the form of lamp-black or hard carbon. Gasification, however, will be complete, so that there will be no subsequent condensable matter in the gas after passing from the generator. This is a practical, continuous process for generating illuminating gas of uniform quality or candle-power and without waste of hydrocarbons.

In case it is desired not to decompose steam in the zones of the generator, a comparatively low temperature, varying between 800° F. and 850° F., is maintained in all of the heaters, and the steam will carry the oil vapors into contact with the heated surfaces where the oil vapors will be split up, so as to produce the greatest possible amount of high illuminants of the olefin series.

While I have shown and described the electric heating tubes arranged in unit sections for convenience of construction and repair, I

wish it understood that my invention is not limited to such specific construction, but that the walls of the generator may be laid up in any convenient manner and the heating tubes placed at suitable intervals in horizontal rows with intervening rows of fire-clay tiling or checker-work. An internally heated electric heating tube, providing for continuous heat at any desired temperature is an important part of my invention.

Having described my invention, what I claim, and desire to secure by Letters Patent, is—

1. A generator for producing gas, comprising a series of superposed unit sections, the sections being alike in form, and each section carrying an electric heater and tiling adapted to be heated thereby.

2. A generator for producing gas, comprising a series of superposed unit sections alike in form, each section carrying a plurality of electric heaters, and a plurality of tiles adapted to be heated by said heaters.

3. A generator for producing gas, comprising a plurality of superposed unit sections, each section being provided with means whereby it may be secured to the next adjacent section or sections, electric heaters carried by each section, and a plurality of tiles likewise carried by each section.

4. A generator for producing gas, comprising a series of superposed unit sections, each section being composed of a metallic shell provided with a lining of non-conducting material adjacent to the shell and an interior lining of refractory material, a plurality of heater pipes extending through said section linings, an electric heater in each of said pipes, and a plurality of tiles extending across the sections adjacent to the pipes.

5. A generator for producing gas, comprising a series of superposed unit sections, each section being composed of a shell provided with a lining of asbestos adjacent to the shell, and an interior fire-brick lining adjacent to the asbestos lining, one or more heater pipes extending through said shell and lining, an electric heater having electrodes in each of said pipes, and a plurality of tiles extending across the sections and adjacent to the pipes.

6. A generator for producing gas, comprising a series of superposed unit sections, each section comprising a shell provided with an inwardly projecting flange, a lining of asbestos adjacent to the shell, a fire-brick lining resting upon the flange, a plurality of pipes extending through said linings,

an electric heater in each of said pipes, and a plurality of tiles above the pipes.

7. A generator for producing gas, comprising a plurality of superposed unit sections, each section comprising a metallic shell provided with an inwardly projecting flange, an asbestos lining adjacent to the outer wall of the shell, fire-brick mounted upon the inwardly projecting flange and abutting against the asbestos lining, a plurality of pipes passing through the shell and lining, means for securing said pipes in position, an electric heater mounted in each of said pipes, and a plurality of tiles located above the pipes.

8. The combination with the walls of a generating chamber having suitable non-conducting material therein, of one or more heater pipes passing through said walls, carbon electrodes in the opposite ends of said pipes, granular resistance material in the pipes between the electrodes, means for admitting a hydrocarbon or a liquid carrying carbonaceous matter in contact with said heater pipes, and a gas outlet pipe, substantially as described.

9. A generator for producing gas, comprising a plurality of superposed sections, each section being provided with fire-brick lining, a series of heater pipes extending through the section, an electric heater mounted in each of said pipes, and means for producing localized intense heat in said heater pipes within the walls of the generator.

10. In a gas generator, the combination with a chamber having non-conducting walls, of pipes extending through the walls, electric heaters in the pipes, a covering of metallic oxids on the outer surfaces of the pipes for preventing the deposit of carbon or lamp-black from hydrocarbon oil on the heater pipes, and means for supplying hydrocarbon oil or vapor to the chamber in contact with said pipes.

11. In a gas generator, the combination with a decomposing chamber, of a series of heater pipes extending therethrough, means in the pipes for producing an intense localized heat in the parts of the pipes within the walls of the generator, and coatings on the pipes for preventing the deposition of carbon thereon.

In testimony whereof I hereby affix my signature in presence of two witnesses.
